Attorney

UNITED STATES PATENT OFFICE.

HENRY G. CORDLEY, OF GLEN RIDGE, NEW JERSEY.

LIQUID-DISPENSING DEVICE.

1,260,334.

Specification of Letters Patent. Patented Mar. 26, 1918.

Application filed January 19, 1917. Serial No. 143,339.

To all whom it may concern:

Be it known that I, HENRY G. CORDLEY, a citizen of the United States, residing at Glen Ridge, in the county of Essex, State of New Jersey, have invented certain new and useful Improvements in Liquid-Dispensing Devices, of which the following is a description, reference being had to the accompanying drawings, forming a part hereof.

10 My invention relates to liquid dispensing devices and has for its object to provide a simple, inexpensive device for dispensing liquid from an inverted bottle by which a measured quantity may be delivered upon a single actuation of the device, and which will be secured to the bottle before it is inverted.

15 With these and other objects hereinafter explained in view my invention consists in the construction and combination of elements hereinafter described and claimed.

Referring to the drawings:

Figure 1 is a central vertical section of a dispensing device embodying my invention showing the measuring chamber filled.

Fig. 2 is a similar view showing the measuring chamber emptied and

Fig. 3 is a top plan view of the clamp for securing the device to a bottle.

30 In the drawings 1 indicates a measuring chamber preferably of glass or porcelain open at both ends, the opening 2 at its upper end being of relatively large size, and necessarily larger in diameter than the outside diameter of the neck of the bottle with which it is to be used, and the lower or discharge opening 3 being of relatively small diameter.

Arranged within the measuring chamber and preferably in line with its vertical axis 40 is a rod 4 carrying at its upper end a cup 5 of a diameter slightly greater than the outside diameter of the neck of the bottle with which it is used so as to be capable, when in raised position as shown in Fig. 2, of in closing the mouth of the bottle.

At its lower end the rod 4 is provided with a disk 6 of rubber or other flexible material adapted to serve as a valve to rest on the walls of the measuring chamber at the 50 upper end of the discharge opening 3. Below the valve 6 an operating rod 7 extends downward through the discharge opening 3 in line with rod 4, the outer portion of this operating rod being bent outward as shown 55 at 8 and then preferably upward and outward to form a convenient handle 9.

The seating cup 5 is preferably provided with means such as downwardly extending wires 10 adapted to contact with the walls of the upper opening 2 so as to keep the sealing cup in central position while permitting it to move freely up and down.

The measuring chamber is provided at its upper end with means for securing it to the neck of a bottle. The means shown consists of a ring 11 of resilient material preferably sheet metal fitting the outside of the upper end of the measuring chamber and secured thereto in any convenient manner as by screws 12. The outer end of this ring 11 is provided with longitudinal slits 14 dividing it into a number of spring arms 15, the outer ends of which are bent inward to form a shoulder 16 to engage the ring 17 about the neck of the bottle 18, and then bent outward as shown at 19 to facilitate placing it on the bottle neck.

The inverted bottle 18 is shown supported by a stand comprising a ring 21 adapted to support the bottle, and legs 22.

In use the device is placed on the bottle when in upright position by simply forcing the spring arms 15 over the ring 17. The bottle may then be inverted and held in inverted position on a stand such as is shown or on any other convenient support. As soon as the bottle with the dispensing device in position on it is inverted the rod 4 drops bringing the sealing cup below the mouth of the bottle and bringing the valve 6 in position to close the discharge opening 3. The contents of the bottle flow out over the edges of the sealing cup and fill the chamber 1 until the liquid reaches the level of the bottle mouth when the flow stops as air can no longer get into the bottle.

When the handle 9 is raised the valve 6 is lifted to permit the liquid to flow out and at the same time the sealing cup filled with liquid is raised into the position shown in Fig. 2 in which position it seals the mouth of the bottle so that no liquid can flow out except that in the measuring chamber, which flows out into a glass 23 or other receptacle. On releasing the handle 9 the rod 4, with its sealing cup and valve, drops and the measuring chamber is refilled.

I may substitute for the sealing cup 5 a valve or other sealing means adapted to be brought into position to close the mouth of the bottle when the rod 4 is raised.

While the device as above described is par-

ticularly adapted for dispensing drinking water it may be used for any other liquids.

Having thus described my invention, what I claim is:—

- 5 1. A dispenser for inverted bottles comprising a chamber open at its upper end to receive the neck of the inverted bottle and having a discharge opening at its lower end, a vertically movable sealing cup within the chamber adapted to inclose the bottle mouth but normally out of position to seal the mouth of the bottle, a valve normally closing the discharge opening and means for simultaneously opening the valve and raising the sealing cup into sealing position.
- 10 2. A dispenser for inverted bottles comprising a chamber open at its upper end to receive the neck of the inverted bottle and having a discharge opening at its lower end, an inwardly opening valve for the discharge opening, a vertically movable rod carrying the valve extending up into the chamber provided at its upper end with a sealing cup adapted to inclose the bottle mouth to seal
- 15 25 the same, the length of the rod between the rod and sealing cup being less than the distance between the inner end of the discharge opening and the mouth of the bottle, so that the sealing cup will be normally out of
- 20 30 position to seal the mouth of the bottle.

3. A dispenser for inverted bottles comprising a chamber open at its upper end to receive the neck of the inverted bottle and having a discharge opening at its lower end, a vertically movable sealing cup within the chamber adapted to inclose the bottle mouth but normally out of position to seal the mouth of the bottle, a valve for the discharge opening, means for opening the valve and raising the sealing cup into sealing position, and means carried by the upper end of the chamber for securing it to a bottle.

4. A dispenser for inverted bottles comprising a chamber open at its upper end to receive the neck of the inverted bottle and having a discharge opening at its lower end, a vertically movable sealing cup within the chamber adapted to inclose the bottle mouth but normally out of position to seal the mouth of the bottle, a valve for the discharge opening, means for opening the valve and for holding the sealing cup in line with the bottle mouth and means for lifting the sealing cup into position to seal the mouth of the bottle.

In testimony whereof I affix my signature this 2nd day of January, 1917.

HENRY G. CORDLEY.
